INVENTOR:

Walter Schmied

UNITED STATES PATENT OFFICE.

WALTHER SCHMIED, OF EGNACH-ON-THE-BODENSEE, SWITZERLAND.

ROTARY MACHINE.

Application filed July 27, 1923. Serial No. 654,282.

To all whom it may concern:

Be it known that I, WALTHER SCHMIED, a citizen of Switzerland, residing at Egnach-on-the-Bodensee, in the State of Thurgovia, Switzerland, have invented certain new and useful Improvements in Rotary Machines, of which the following is a specification.

My invention relates to improvements in rotary machines, and more particularly in machines comprising a plurality of chambers for successively compressing elastic fluids. As is known to those skilled in the art, the temperature of the elastic fluid is raised by the compression, so that it is necessary in some cases to perform the compression in two stages and to include cooling means intermediate the stages. The object of the improvements is to provide a system in which separate compressors are dispensed with, and with this object in view I provide a conduit for successively connecting a pressure chamber of higher pressure with a pressure chamber of lower pressure, and I include cooling means in the conduit connecting the said chambers. Thereby a part of the fluid which has been compressed and heated is successively taken from the chambers of higher pressure, cooled, and thereafter passed into the chambers of lower pressure, where it cools the fluid which has been partly compressed and heated, so that the final temperature of the fluid does not exceed the degree allowed for practical reasons.

For the purpose of explaining the invention an example embodying the same has been shown in the accompanying drawings in which the same reference characters have been used in all the views to indicate corresponding parts. In said drawings,

Fig. 1, is a vertical cross-section of a rotary compressor taken on the line 1-1 of Fig. 2,

Fig. 2, is a longitudinal section taken on the line 2-2 of Fig. 1, and

Fig. 3, is a detail sectional view taken on the line 3-3 of Fig. 2.

In the example shown in the drawings the compressor comprises a casing 1 having suction and pressure passages 2 and 3, a rotary piston 4 mounted eccentrically within the casing 1, and a plurality of blades 5 reciprocating in radial slots 6 of the piston and adapted to be forced outwardly by centrifugal action. At a part intermediate the suction and pressure passages 2 and 3 there are an outlet passage 7 and an inlet passage

8, which passages are connected with each other by a branch pipe 14 including a cooling coil 9 disposed within a cooler 10, a valve 11, and a small fan 12. The outlet passage 7 communicates with a part of higher pressure, and the inlet passage 8 with a part of lower pressure.

As appears from Fig. 2, the passages 7 and 8 are preferably disposed respectively at opposite ends of the casing 1, and they are preferably arranged so that they communicate temporarily with the same chamber provided between successive blades 5.

The operation of the system is as follows: The piston 4 rotates in the direction of the arrow 13. By centrifugal action or by other means the blades 5 are held in contact with the inner wall of the casing 1, so that the space between the casing 1 and the piston 4 is divided into separate chambers, which chambers move in the upper part of Fig. 1 in the direction from the left to the right and in the lower part from the right to the left. While moving through the section of the machine located at the left of the vertical median plane of Fig. 1 the capacity of the chambers is increased, so that they take in the elastic fluid, and when moving through the right hand part of the machine the capacity of the chambers is reduced, so that the fluid is gradually compressed. If now the blades 5 are in the positions shown in Fig. 1 in broken lines, a chamber of higher pressure communicates with the outlet passage 7 and a chamber of lower pressure with the inlet 8. Therefore a part of the fluid confined within the chamber 7 flows through the pipes 14, the cooling coil 9 and the inlet passage 8 into the chamber of lower pressure, the volume of the fluid flowing from one chamber to the other being regulated by valve 11. After the fluid coming from the chamber of higher pressure has been cooled within the cooling system 9, 10, it cools the fluid combined within the chamber of lower pressure. The fluid confined within the chamber of lower pressure is in part

mixed with the cooled gas coming from the chamber of higher pressure, and a part is forced into the part of the said chamber which is opposite to the inlet passage 8. Therefore the fluid is made to flow through the chamber in the direction from the inlet passage 8 to the discharge passage 7. Preferably said passages are disposed so that they communicate temporarily with parts of their cross-sectional area or with their whole area

with the same fluid chamber, as has been indicated in Fig. 1.

If now by the rotation of the piston 4 the chamber which before communicated with 5 the inlet passage 8 is brought into communication with the discharge passage 7, a part of the fluid escapes by reason of the increased pressure, and more particularly the part which is next to the discharge passage and 10 which is at higher temperature than the part found at the side of the inlet passage. The movement of the fluid is started by some kind of blowing action which takes place when both passages 7 and 8 open into the same 15 chamber, and it is supported by the fact that within the pipes 14 and the coil 9 the fluid is in continuous motion in a direction towards the inlet passage 8. In some cases I provide additional means for circulating 20 the fluid, such as the blower or fan 12 included in the pipes 14, which blower is provided with driving means of its own, or which is driven by the compressed fluid within the cooling coil 9. After the chamber 25 has passed beyond the outlet passage 7, the compression of the cooled fluid is completed, the final temperature being reduced as compared to a system in which no cooling means are provided. By cooling the fluid the 30 power required for driving the compressor is reduced.

While in describing the invention reference has been made to a particular example embodying the same I wish it to be understood that my invention is not limited to the construction shown in the drawings, and that various changes may be made in the general arrangement of the apparatus and the construction of its parts without 35 departing from the invention.

I claim:

1. In a system of the class described, the combination, with a rotary machine comprising fluid chambers of gradually decreasing capacity and increasing pressure, of a conduit communicating with successive chambers of different pressure and including cooling means.

2. In a system of the class described, the combination, with a rotary machine comprising fluid chambers of gradually decreasing capacity and increasing pressure, of a conduit communicating with chambers of different pressure and including cooling means, said conduit having its ends arranged for opening into each of the chambers at opposite ends thereof.

3. In a system of the class described the combination, with a rotary machine comprising fluid chambers of gradually decreasing capacity and increasing pressure, of a conduit communicating with chambers of different pressure and including cooling means, the ends of said conduit being so 60 disposed circumferentially of the machine 65 that they open temporarily into the same chamber.

4. In a system of the class described the combination, with a rotary machine comprising fluid chambers of gradually decreasing capacity and increasing pressure, of a conduit communicating with chambers of different pressure and including cooling means, said conduit opening into the chambers at opposite ends thereof and its ends 70 being spaced circumferentially of the machine so that they open temporarily into the same chamber.

5. In a system of the class described, the combination, with a rotary machine comprising fluid chambers of gradually decreasing capacity and increasing pressure, of a conduit communicating with chambers of different pressure and including cooling and 75 circulating means.

6. In a system of the class described, the combination, with a rotary machine comprising fluid chambers of gradually decreasing capacity and increasing pressure, of a conduit communicating with chambers of different pressure and including cooling and 80 circulating means and means for regulating the flow of the fluid.

7. In a system of the class described, the combination, with a rotary machine comprising fluid chambers of gradually decreasing capacity and increasing pressure, of a conduit communicating with chambers of different pressure and including cooling and circulating means and means for regulating 95 the flow of the fluid.

8. In a system of the class described the combination, with a rotary machine comprising fluid chambers of gradually decreasing capacity and increasing pressure, of a conduit communicating with chambers of different pressure and including cooling and 100 circulating means, said conduit opening into the chambers at opposite ends thereof and its ends being spaced circumferentially of the machine so that they open temporarily into the same chamber.

9. In a system of the class described, a plurality of moving fluid chambers increasing and decreasing in volume, a conduit 115 having its opposite ends disposed to conduct fluid pressure from one end of a chamber to the opposite end of a succeeding chamber, and means for cooling the fluid as it passes through the conduit.

10. In a system of the class described, a movable body having fluid chambers increasing and decreasing in volume progressively, means for conducting fluid pressure from one chamber to a succeeding chamber, and means for cooling the fluid prior to being discharged into the said succeeding chamber.

In testimony whereof I affix my signature.

WALTHER SCHMIED.
